METHOD AND APPARATUS FOR EVAPORATING SULPHATE RESIDUAL LIQUOR

Börje Sune Nyquist, Sandviken, Dynas, Sweden,
assignor to Aktiebolaget Svenska Flaktfabriken,
Stockholm, Sweden, a joint-stock company of
Sweden

Application March 17, 1939, Serial No. 262,486
In Sweden January 5, 1937

2 Claims. (Cl. 159—10)

This invention relates to the treatment of residual liquor which is produced in the sulphate process of manufacturing pulp from cellulosic fibrous materials.

In the manufacture of pulp according to the sulphate process the sulphate residual liquor (black liquor) is concentrated to a viscous condition by means of disc evaporators (Scheibenverdampfer) in the recovery process. This viscous liquor is then evaporated to dryness in rotating furnaces and finally burnt in soda melting furnaces, the melted soda being then caustified with lime, whereby so called white liquor is obtained, which is used in the cooking process.

The present invention relates to a method according to which the sulphate residual liquor by means of, for instance, flue gases may be directly evaporated to dryness.

According to the invention a film of the liquor is caused to follow a rotating body, the surface of which is, at least partially, swept by hot gases (moving either in the direction of travel of, or counter to the direction of, the body) in such a manner that the liquor adhering to the body is evaporated to dryness by the action of the hot gases, the dried material being then scraped off by scraping means.

The apparatus according to the invention may comprise a container for the liquor having an inlet and outlet for the hot gases, a rotary body being provided therein, in the path of the hot gases from the inlet to the outlet, in such a manner that it partially dips into the liquor, and scraping means provided close to the surface of the body, the said scraping means removing the dried material from the body.

The rotary body may comprise a plurality of spaced discs mounted on a rotatable shaft; or, it may comprise a substantially cylindrical body carrying on its periphery a plurality of spaced annular projections of disc form integral with said body, the cylindrical body being supported for rotation about the axis thereof. In either event, the scraping means is positioned within the grooves made by, and contacts the surfaces of, the discs or disc-like annular projections in a manner adapted to remove from said surfaces material carried thereon.

In the accompanying drawing one embodiment of an apparatus according to the invention is illustrated. Fig. 1 shows a section through the device perpendicularly to the shaft of the rotary body. Fig. 2 is a section of one end portion of the device, taken perpendicularly to the section of Fig. 1, and Fig. 3 shows a detail.

The rotary body comprises a horizontal shaft 1, on which there is provided a number of circular discs 2 of sheet-metal which are kept at a distance from each other by means of spacers 3. The shaft 1 is rotatably mounted in a container 4 of about cylindrical shape, the surface of which substantially corresponds to the periphery of the circular discs 2. The container 4 is filled with sulphate residual liquor 5 to such a level that the discs 2 partially dips into the same. A pipe 6 through which hot exhaust gases are supplied, for instance from the soda melting furnace, is provided with an opening that extends all along the container 4. In each space between the circular discs 2 there is provided an inclined scraper 7 which extends as far as to the spacer 3.

The shaft 1 rotates in the direction of the arrow and the liquor will adhere to the discs 2. These discs will during the rotation meet a current of hot gases from the pipe 6. The speed of rotation of the shaft 1 is adjusted in such a manner that the liquor adhering to the discs has been evaporated to dryness when it reaches the scrapers 7. These scrapers 7 scrape off the dry material, which falls down into a channel 8 located beneath the scrapers, and having a transport screw 9 provided therein. The cooled gases escape through the pipe 10 to, for instance, the stack. In order to allow the entering gases to contact the liquor and the portions of the discs located beneath the scrapers (the scrapers prevent the gases to escape this way) there is provided a slot 11 between the container 4 and the holder 12 for the scrapers. This slot, which extends all along the container 4, communicates with a channel 13, connected with the pipe 6 through conduit 14 as indicated by dotted lines in Fig. 1. The size of the slot 11 is so adjusted that a smaller part of the hot gases flows in beneath the scrapers.

The discs 2 are preferably constructed in such a manner that they grow thinner towards the periphery (see Fig. 3).

Having now described my invention, what I claim as new and desire to secure by Letters Patent is:

1. In an apparatus for evaporating sulphate residual liquor to dryness by means of hot gases, the combination with a chamber whose lower part provides a container for liquor, a gas inlet extending along one side of said chamber, a gas outlet at an opposite side of said chamber, means for passing a stream of hot gases through said chamber from inlet to outlet, a rotary body positioned between said inlet and said outlet and

in and substantially transverse to the path of such stream, said rotary body comprising a plurality of annular projections of disc form and being so located that said annular projections partially extend into said liquor-containing part of said chamber, and scraper means cooperating with surfaces of said annular projections to remove material therefrom and so positioned as to constitute a baffle directing the flow of gas from inlet to outlet over the axis of said rotary body, of a supplemental elongated opening in said chamber along the side thereof containing said inlet, said supplemental opening being below said scraper means and adjacent the liquor-containing part of said chamber, and means for introducing into the chamber, through said supplemental opening, a supplemental stream of hot gas for traversing the lower portions of said annular projections.

2. In the method of drying sulphate residual liquor involving the steps of maintaining a body of the liquor, continuously passing a current of hot flue gas over said body, continuously raising a film of said liquor, on a moving support, above the body of liquid and into the current of hot flue gas, maintaining the film in contact with the hot flue gas for an interval sufficient to evaporate the film to substantial dryness, and continuously removing the dry film from the moving support, the improvement which consists in dividing the current of hot flue gas into two separate currents prior to passage thereof into contact with the liquor, passing one of said currents over the surface of the body of liquor, and separately passing the other of said currents over said film of liquor.
